UNITED STATES PATENT OFFICE

WILLIAM T. MORGAN, OF NEODESHA, KANSAS

SANITARY BEAD OPENING

Application filed January 15, 1930. Serial No. 420,920.

This invention relates broadly to the building of door and window openings in houses, office buildings, sanitariums, hospitals, schools and the like, and the primary object of this invention is to provide and includes bead for the door and window opening, the bead being of such a nature as to insure a neat and attractive appearance.

A further object of the invention is the provision of a bead as may be readily secured in place in such a manner as to eliminate all undesirable and unnecessary corners, crevices and the like in which dust and vermin may accumulate.

A still further object of the invention is to provide a means of the character above mentioned, which may be readily and easily put into place at the opening in the wall without necessitating any material alterations in the conventional door or window frame and wherein the bead is preferably formed of wood, painted, varnished or otherwise finished to conform with the door or window frame with which it is used and further, wherein the wooden bead is simple in construction, may be used with any type of door or window opening, and further, wherein the bead will otherwise prove itself well adapted for the purpose designed.

Other objects and advantages of the invention will become apparent during a study of the following description, taken in connection with the accompanying drawings, wherein:

Figure 1 is a fragmentary elevational view of a wall having a door opening formed therein for more clearly illustrating the manner in which the present invention is to be carried out,

Figure 2 is a transverse sectional view showing the use of the improved bead in conjunction with a door opening in the wall,

Figure 3 is a fragmentary horizontal sectional view of the door opening for more clearly illustrating the manner of forming the opening prior to the installation of the bead as shown in Figure 2,

Figure 4 is a horizontal sectional view taken through a window structure showing the manner of alining the laths and plaster

of the wall at the window opening prior to the bead being installed,

Figure 5 is a similar view showing the bead installed,

Figure 6 is a vertical fragmentary sectional view through a window structure for more clearly illustrating the use of my improved bead with the sub-sill of the window structure.

With reference more in detail to the drawings, wherein like numerals refer to corresponding parts throughout the several views, I have indicated the wall of a building by the reference character W, the studding secured to the wall in the usual well known manner designated by S. As shown in Figure 1, the wall W is provided with an entrance or door opening O. The door frame in the opening is designated generally by the reference character F.

In forming, or completing the walls W having the door opening O formed therein, the usual laths L are nailed or otherwise affixed to the studding S, the end of the laths at opposite sides of the door opening overlapping the inner and outer faces of the jamb 5 of the door frame F, the end of the laths terminating inwardly from the door opening as shown to advantage in Figure 2.

In the method adopted, and as shown to advantage in Figure 3, after the laths L are affixed to the studding and jamb 5 of the window frame as just described, a ground of cheap wood which may be either a studding or lath is utilized in the nature of a ground as indicated at 6, the ground being nailed to the members 5 of the door frame about the edge of the opening in the wall, the thickness of which ground 6 will be equal to the combined thickness of the laths and the plaster P as shown to advantage in Figure 3.

The ground 6 will act as a guide for a trowel which smooths plaster into place the outer face of the plaster being flush with the outer face of the ground.

When the plastering operation has been completed, the ground 6 is then removed and then substituted therefor as shown to advantage in Figure 2 is my improved bead or mold-

ing designated generally by the reference character B.

As shown to advantage in Figure 2, the bead or molding B is secured to the frame members 5 of the frame F inwardly from the opening to project from the frame members 5 and said bead is disposed directly against the edges of the laths L and the plaster P, and the bead on its outer longitudinal edge 10 is provided with an inwardly directed locking flange 7 which overlaps the plaster for locking the plaster as shown to advantage in Figure 2.

From the foregoing then it will be seen 15 that the edges of the wall about the opening O will present a neat, clean, attractive and well finished appearance, and that the bead B may be set in place without in any way altering either the conventional structure of 20 the door frame, the door D, or the conventional door stop E which stop E is secured in the usual well known manner to one of the vertical frame members 5, commonly known as the door jamb.

25 It will also be appreciated from the foregoing, that as comprehended by the present invention, that the usual wall frame members are used as door jambs, without affecting any change in construction, and that to the 30 wall frame member forming the door jamb there is applied the laths and plaster without necessitating any change in construction of the frame door jamb and without the aid of any other material except the common 35 or ordinary wood ground as illustrated in the above description, after which upon removal of the ground, there is applied a substantially L-shaped wood bead as shown thus forming a complete and attractively finished door 40 opening, which bead may be finished as to conform to the door and other trimming in the room.

In Figures 4 and 5 I have shown fragmentarily a window frame opening, the window being of the conventional style and embodying the usual vertical frame members 9, the outside stop 10 and the parting strip 11. As herein shown, the laths L have their ends secured to the inside vertical edge of the window frame member 9, the end of the laths terminating flush with the edge of the window opening, and the plaster P terminating flush with the end of the lath as shown.

In this connection, the ground is designated by the reference character 6', and in this illustration is preferably of elongated rectangular configuration being in the nature of a conventional lath whereas the ground strip 6 as used may be a conventional stud 60 ding. As shown in Figure 4, the ground 6' has its inner end in spaced parallelism with one side edge of the parting strip 11, said ground 6 being nailed or otherwise secured as at 12 to the window frame member 9 flush 65 against the adjacent end of the laths, L and

plaster P, the function of the ground 6' however being the same as the ground 6.

As shown in Figure 5, in this instance, the bead or molding is designated generally by the reference character B', the molding or 70 bead B' being also of L-shaped configuration, the same as the bead B, the flange 7' of the bead B' overlapping the plaster, while at its opposite end the vertical end edge of the bead B' extends inwardly from the outer edge of 75 the window frame 9 to terminate in spaced parallelism with the parting strip 11, so that obviously in window construction, the bead also serves the function of an inside stop, cooperating with the parting strip 11 in the 80 same manner as the outside stop 10 to provide channel guides for the window sash 15.

If desired, nails or other securing elements 14 may be driven through the flange 7', the plaster P and the laths L and into the frame 85 members 9 for more securely anchoring the bears B' in place.

In Figure 6 I have shown the beading embodying the features of my invention, and in this instance the beading designated by the reference character B2 is secured to the forward edge of the subsill 13 of the window frame, and the flange 7a of the beading B2 overlaps the adjacent end portion of the plaster P at the meeting edges of the plaster and 95 the subsill.

Thus it will be seen that in this connection, the beading is also adaptable for use as the inner finishing strips of a window sill.

From a study of Figures 4 to 6 inclusive, and from the foregoing description, relative thereto, it will be seen in regard to the window opening, the laths and plaster are applied directly to the inside edge of the window jamb as shown without necessitating any change in construction of either side jamb or head jamb and the laths and plaster are so applied only with the aid of a common lath for a ground to guide the plaster trowel as before described, and further that the inner edge of the subsill of the window is fashioned at the bottom of the window frame so that it becomes plaster ground, being so extended inwardly to conform to the thickness of the lath and plaster and also top of subsill is 110 fashioned so that when laths and plaster are so applied it is at substantially right angles to the wall.

Furthermore, as will be appreciated, the L-shaped bead is used all around the opening to act as a window sash guide at the sides and top of the window as is apparent from Figures 4 and 5 and also to act as a stool at the bottom of the window as shown in Figure 6, said L-shaped means thus further functioning as a finishing member for the window opening.

It is thought that from the foregoing description, taken in connection with the accompanying drawings, a clear understanding 120 125 130

of the operation, construction, utility and advantages of an invention of this character will be had by those skilled in the art without a more detailed description.

- 5 It is also thought, that from the foregoing, it will be readily appreciated a door or window opening in which is disposed the usual frame will present a neat and attractive finish, be free of corners and crevices when 10 equipped in the manner as above set forth with a finishing bead embodying the features of the present invention and through the medium of which molding or bead, the plaster will be locked to the laths, the flange of the 15 bead acting as a protection for the plastering at that end of the plaster adjacent the edge of the door or window opening along the sides, and as will be apparent along the top of the opening.
- 20 Even though I have herein shown and described the preferred embodiment of my invention, it is to be understood that the same is susceptible to changes fully comprehended by the spirit of the invention as herein described, and the scope of the appended claims.

While I do not claim to be the original inventor of the L-shaped or right angle mold, since in some of its relative forms it has been in common practice heretofore a number of 30 years, I do claim all such forms of beading as here used for door and window openings, and in combination with door and windows for use with the door and window jambs and the laths and plaster of the wall at the edges 35 of the door and window openings all in the manner as hereinbefore described.

Having thus described my invention, what I claim as new is:

40 1. A wall having an opening, a closure supporting frame in the opening, a bead formed of wood, said bead being of L-shaped formation in cross section, and having one flange thereof secured to the frame, and the other flange thereof extending in spaced 45 parallelism to the frame, a plaster coat on the wall abutting the first mentioned flange of said bead, the last mentioned flange of said bead being disposed in overlapping relation with the adjacent edge of said plaster coat and the first mentioned flange of said bead providing a closure stop for the frame.

2. A wall having an opening, a window frame in the opening and provided with a window stop, a bead formed of wood, said 55 bead being of L-shaped formation in cross section, and having one flange thereof secured to the frame, and the other flange thereof extending in spaced parallelism to the frame, a plaster coat on the wall abutting the first mentioned flange of said bead, the last mentioned flange of said bead being disposed in overlapping relation with the adjacent edge of said plaster coat, laths interposed between said plaster coat and the wall, said 60 laths having their ends in abutting relation

with the first mentioned flange of said bead, said first mentioned flange extending in spaced parallelism to said window stop to accommodate therebetween a window sash.

3. A wall having an opening, a window frame in the opening, a bead formed of wood, said bead being of L-shaped formation in cross section, and having one flange thereof secured to the frame, and the other flange thereof extending in spaced parallelism to the frame, a plaster coat on the wall abutting the first mentioned flange of said bead, the last mentioned flange of said bead being disposed in overlapping relation with the adjacent edge of said plaster coat, laths interposed between said plaster coat and the wall, said laths having their ends in abutting relation with the first mentioned flange of said bead, and the thickness of the plastic coat and laths being equal to the space between said wall and said second flange, and said one flange adapted to constitute a sash stop for the window frame.

4. In combination with a window frame, arranged in the window opening of a building, a finishing bead, L-shaped in cross section and of a length corresponding substantially to the length of a selected one of the members of the window frame, said bead having one flange thereof overlapping said one frame member, and the other flange thereof overlapping the adjacent edge portion of the wall plaster, that portion of the first mentioned flange projecting laterally of the building wall providing a ground for the corresponding edges of the laths and wall plaster at the edge of the window opening, said first mentioned flange providing a sash stop for the window frame.

5. In combination with a window frame member and a sash stop extending longitudinally thereof, of a bead formed of wood and secured to said frame member in spaced parallelism to said stop to provide a second stop cooperating with the first mentioned stop, said bead having a portion thereof projecting beyond an adjacent edge of said frame member, to provide a ground for the plaster wall terminating flush with the outer surface of said frame member.

In testimony whereof I affix my signature.
WILLIAM T. MORGAN.
